UNITED STATES PATENT OFFICE.

ROBERT II. POSTLETHWAITE, OF SAN FRANCISCO, CALIFORNIA, ASSIGNOR
TO THE RISDON IRON AND LOCOMOTIVE WORKS, OF SAME PLACE.

DESIGN FOR A BEARING-BRACKET.

SPECIFICATION forming part of Design No. 28,161, dated January 11, 1898.

Application filed December 6, 1897. Serial No. 660,977. Term of patent 14 years.

To all whom it may concern:

Be it known that I, ROBERT II. POSTLETHWAITE, a subject of the Queen of Great Britain, residing in the city and county of San Francisco, State of California, have invented and produced a new and original Design for a Bearing-Bracket, of which the following is a specification, reference being had to the annexed drawing, showing the design in outline.

The present design for a bearing-box consists of a base or wall plate A, united to a V-shaped frame A', so as to form the base thereof. Within the V-shaped frame is a triangular-shaped plate B, which serves as a strengthening-web for the frame. The apex of the said frame terminates in a bearing-box B', from which outwardly projects a forwardly-curved arm C, which carries a bearing-box C' at approximately a right angle to the bearing-box B' and in the same horizontal plane. In each bearing-box is formed a shaft-open-

ing b and in the face or wall plate A a series of bolt-openings b'.

The essential feature of the design consists of a face or wall plate united to a V-shaped frame carrying at its apex a bearing-box and provided with an outwardly-projecting forwardly-curved arm carrying a bearing-box approximately in the same horizontal plane, but at an angle to the bearing-box of the said V-shaped frame.

Having thus described my invention, what I claim as new, and desire to secure protection in by Design Letters Patent, is—

The design for a bearing-bracket substantially as shown and described.

In testimony whereof I affix my signature, in the presence of witnesses, this 30th day of October, 1897.

ROBERT II. POSTLETHWAITE.

In presence of—

N. A. ACKER,
LEE D. CRAIG.
